[57] CLAIM

The ornamental design for a support clip for a louver or
the like, as shown and described.

DESCRIPTION

FIG. 1 is a perspective view of a support clip for a
louver or the like showing my new design;

FIG. 2 is a side elevational view thereof, the louver
being shown in broken lines for illustrative purposes
only;

FIG. 3 is a front elevational view thereof;

FIG. 4 is a rear elevational view thereof; and

FIG. 5 is a top plan view thereof.
